UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

DRESS-SHIELD.

1,277,916.

Specification of Letters Patent.

Patented Sept. 3, 1918.

Application filed August 3, 1917. Serial No. 184,218.

To all whom it may concern:

Be it known that I, VICTOR GUINZBURG, a citizen of the United States, and a resident of the city, county, and State of New York, 5 have invented a certain new and useful Improvement in Dress-Shields, of which the following is a specification.

This invention relates to certain improvements in dress shields such as are adapted 10 for use for the protection of garments at the juncture of the sleeves from the effects of perspiration and the object of this invention is to provide, in an article of this character, an improved means for holding it 15 in place in the garment, so as to prevent the shield from being crumpled up and displaced by movement of the arms or otherwise.

Heretofore dress shields have been 20 secured in place in garments, at the juncture of the sleeves and body of the garment, by pins or stitches which extended through the body of the shield, thus ruining the rubber interlining of the shield by puncturing it. 25 In my improved dress shield I overcome these disadvantages by providing the shield with an integrally formed supplemental strip which does not materially thicken or add any additional bulk to the shield at the 30 juncture of the sleeve and body of the garment, and yet provides a means for securing the shield in proper position without in any way causing damage to the shield itself.

With these objects, and other objects 35 which may hereinafter appear, in view, I have devised the particular combination of parts hereinafter disclosed and more particularly pointed out in the claims appended hereto.

Reference is to be had to the accompanying drawings, forming a part hereof, in which,

Figure 1 is a front elevation of a dress shield provided with my improvement,

Fig. 2 is a sectional view on the line 2—2 of Fig. 1, looking in the direction of the arrows,

Fig. 3 is a front view of a portion of the inside plies of the shield showing the particular form of overstitching used in securing these two inside plies together, and

Fig. 4 is a sectional view showing the two inside plies secured together and reversed to form the attaching strip between them.

Throughout the various views of the

drawing similar reference characters designate similar parts.

In the preferred embodiment of my invention, as disclosed in the accompanying drawing, 1 indicates the dress shield which is of the usual form, consisting of two crescent shaped flaps 2 and 3, united at their upper edges on a concave line. It will be understood that one of the wings projects into the sleeve of the wearer with the other wing 44 extending into the body of the garment.

Each of the wings 2 and 3 is formed of an inner ply 5 and an outer ply 4, both of these plies being preferably of textile material or the like and interposed between these 70 plies is a sheet of protective material 6 such as rubber or the like. The outer plies 4 are stitched together at their upper edges as at 7, in the usual manner. The inner plies 5, however, are stitched together at the 75 upper edges by the particular form of stitching 9, known as overstitching. It will thus be seen that when the inner plies 5 are reversed, as disclosed in Figs. 2 and 4, a strip of material 8 will depend downwardly from 80 the concave upper edge of the shield, between its flaps. This strip of material 8, is as can be readily seen from the drawings, formed by the overstitching which has its 85 inner line extending some distance from the upper edges of the plies 5.

It will be readily seen that the width of the strip 8, thus formed, is readily regulatable by the size of the stitches 9 and it will be further noted that the particular form of 90 overstitching 9 shown in the drawing is not absolutely necessary, as any form of stitching which extends on a line spaced some distance from the edges of the plies 5 to produce a downwardly depending, integrally 95 formed attaching strip, is adaptable for use in this connection.

The strip 8, produced as above described, is readily attachable to the garment at the armhole seam, and the dress shield is securely held in place at all times without being injured in any way by the stitches which secure the shield to the garment. It will be further noted that the manner in which the attaching strip 8 is produced is 100 economical, as it makes use of material heretofore wasted and causes no additional thickness or bulk incidental to the addition of a separately attached strip. The edges of the flaps 2 and 3 are suitably reinforced 105

as at 10 by the form of overstitching above described.

From the foregoing, it is obvious that my invention is not to be restricted to the embodiment herein shown, but is broad enough to cover all structures coming within the scope of the annexed claims.

Having described my invention, what I claim is:

- 10 1. An article of the class described, comprising a pair of flaps formed with inner and outer plies, a means for attaching the article to a garment, comprising an integral attaching strip, the inner plies being 15 stitched together adjacent their upper ends, portions of said ends depending downwardly between the inner plies and having

their edges secured together to form said attaching strip.

2. An article of the class described comprising a pair of flaps secured together at their upper edges and having inner and outer plies, said inner plies being secured together adjacent their upper edges by overstitching to form an attaching strip, said strip depending downwardly between said inner plies and extending co-extensive with the line on which the two flaps are secured together.

Signed at the city of New York, county of New York and State of New York, the 27th day of July, 1917.

VICTOR GUINZBURG.
